CLAIM

The ornamental design for a water bottle with nozzle, as shown and described.

DESCRIPTION

FIG. 1 is a right view of a water bottle with nozzle showing our new design;

FIG. 2 is a left view thereof;

FIG. 3 is a rear view thereof;

FIG. 4 is a front view thereof;

FIG. 5 is a bottom view thereof;

FIG. 6 is a top view thereof;

FIG. 7 is an exploded perspective view thereof, showing the lid separated from the bottle; and,

FIG. 8 is a perspective view of the water bottle with nozzle showing the nozzle in raised position, and handle in a lower position.
